UNITED STATES PATENT OFFICE

ROBERT E. GRACE, OF BARBERTON, OHIO

JAR LIFTER

Application filed April 16, 1932. Serial No. 605,695.

The present invention relates to a device for lifting jars and the like and has for its object to provide a device of this nature which is exceedingly simple in its construction, easy to manipulate, inexpensive to manufacture, thoroughly efficient and reliable in use and operation and otherwise well adapted to the purpose for which it is designed.

10 With the above and numerous other objects of the invention as will become apparent during the study of the following description, taken in connection with the accompanying drawings wherein:

15 Figure 1 is an elevation of the device embodying the features of my invention showing the same engaged with the neck of a jar.

Figure 2 is a similar view taken at right angles to that shown in Figure 1, and

20 Figure 3 is a sectional view taken substantially on the line 3—3 of Figure 1.

Referring to the drawings in detail it will be seen that numeral 5 denotes a bar, the upper end of which is bent to provide a handle 6. The bar 5 is provided intermediate its ends with a longitudinally extending slot 7.

A pair of rods 8 are twisted and curved at one end as at 9 while the other ends are offset oppositely at 10. The extremities of 30 the offset ends straddle the bar 5 and have a pin 11 therein extending through the slot 7 to slide in said slot 7. A pair of links 12 are pivoted to the end of the bar 5 as at 14 and pivoted to intermediate portions of the rod 8 as at 15. Arcuate jaws 16 are engaged on the extremities of the ends 9 as at 17 to engage with the neck of the jar. It will be seen that by lifting up on the handle 6 the links swing the rods 8 inwardly to engage 40 the jaws 16 tightly with the jar. To release the jar 16 it is only necessary to push down on the handle 6.

It is thought that the construction, operation, utility and advantages of this invention will now be quite apparent to those skilled in this art without a more detailed description thereof.

The present embodiment of the invention has been described in considerable detail 50 merely for the purpose of exemplification

since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A jar lifter of the class described including an elongated bar having a longitudinally extending slot formed in an intermediate portion thereof, a pair of rods connected at one end by a pin which extends through the slot, the other ends of the rods being curved inwardly, arcuate jaws on the extremities of said other ends, and a pair of links pivoted to intermediate portions of the rods and pivoted to the end of the bar, said rods being offset at their ends adjacent the pin and having their other ends twisted, said rods, said link and said bar being formed of flat material.

In testimony whereof I affix my signature.

ROBERT E. GRACE.
